COMBINATION CHAIR-DESK

Herbert E. Williams, San Antonio, Tex., assignor to
American Desk Manufacturing Company, Temple,
Tex., a corporation of Texas

Filed Apr. 1, 1963, Ser. No. 74,240

Term of patent 14 years

(Cl. D33—11)

FIG.1

FIG.2

FIG.3

FIGURE 1 is a perspective view of a combination chair-desk embodying my new design;

FIGURE 2 is a front elevational view thereof;

FIGURE 3 is a side elevational view thereof;

FIGURE 4 is a rear elevational view thereof;

FIGURE 5 is a top plan view thereof; and

FIGURE 6 is a bottom plan view thereof.

The dominant features of my design reside in those portions shown in full lines on the drawing.

I claim:

The ornamental design for a combination chair-desk, substantially as shown and described.
